George W. Smith.

BY A. M. Pierce.

Associate ATTORNEY

UNITED STATES PATENT OFFICE.

GEORGE W. SMITH, OF DES ARC, ARKANSAS.

CAR-COUPING.

SPECIFICATION forming part of Letters Patent No. 295,829, dated March 25, 1884.

Application filed June 21, 1883. (No model.)

To all whom it may concern:

Be it known that I, GEORGE W. SMITH, of Des Arc, in the county of Prairie and State of Arkansas, have invented certain new and useful Improvements in Car-Couplings, of which the following is a full, clear, and exact description, reference being had to the accompanying drawings, and to the letters of reference marked thereon.

10 My invention relates especially to that class of car-couplings wherein mechanism is employed for automatically putting the link in place in the draw-head and dropping the coupling-pin therein as the cars come together; and my invention has for its object the provision of a device whereby such automatic coupling is easily and unfailingly effected.

My invention consists, essentially, in a draw-head attached to or forming a part of a draw-bar, said draw-head being provided at its lower side with a sliding lip, which may be drawn out to catch and raise the link to place as the cars approach each other. The sliding lip is operated by means of an arm pivoted beneath the draw-head, a cord or chain passing from said arm to a convenient point for manipulation. The coupling-pin is linked to an arm pivoted to the upper side of the draw-head, near the body of the car, a curved arm having a projection thereon engaging with the first-mentioned arm. This curved arm or lever extends through the draw-head, engaging at its lower extremity with a pin projecting from a lever leading to a convenient point for manipulation. The curved lever also engages with a straight bar recessed in the draw-head and projecting from the face thereof when the coupling-pin is raised to permit the link to enter.

40 The operation of my improved coupling is as follows: The cord is first pulled, projecting the lip at the lower side of the mouth of the draw-head, and the coupling-pin is raised by means of the lever, the movement of said lever throwing out the straight bar recessed in the draw-head. As the cars approach each other, the link strikes the lip, passing into the mouth of the draw-head. The draw-head upon the approaching car pushes the lip back to place, and by striking the projecting bar trips the arm sustaining the coupling-pin, letting it fall to place, completing the process of

coupling without exposing the brakeman to danger.

In the drawings, Figure 1 is a perspective view of my improved car-coupling. Fig. 2 is a plan view of the device when the upper portion of the draw-head is removed. Fig. 3 is a vertical longitudinal section at line *x x* of Fig. 2.

Like letters of reference, wherever they occur, indicate corresponding parts.

A is the frame inclosing the draw-head and draw-bar.

B is the draw-bar, held in place by blocks C.

D is the draw-head, and E is the sliding lip thereof, having a slot, *e*, therein, through which a pin, *e*, passes, holding the lip against too great longitudinal movement.

F is an arm, pivoted at *f*, and having a cord or chain, G, attached thereto, passing through staples *g* to a convenient point upon the body of the car.

H is the coupling-pin, passing through a perforation, *a*, in the draw-head and the slot *e* in lip E. Pin H is attached to an arm, I, said arm extending to a projection, *b*, where it is pivoted. J is a bent lever or arm, pivoted in the draw-head, and having a projecting arm, K, passing beneath arm I.

L is a long lever fulcrumed upon the side of frame A, and having a pin, *l*, projecting therefrom, adapted and arranged to engage with or bear against lever J.

M is a bar recessed in the draw-head and taking against lever J, the movement of bar M being regulated by a projection, *m*, thereon working in a recess in the side of the slot or recess.

Having now fully described my invention, what I claim as new therein, and desire to secure by Letters Patent, is—

1. In a car-coupling of the character herein specified, the combination, with coupling-pin H and arm I, of bent lever J, having projecting arm K, and lever L, bearing pin *l*, substantially as shown and described.

2. In a car-coupling of the character herein specified, the combination, with coupling-pin H and arm I, of bent lever J, having projecting arm K, lever L, bearing pin *l*, and bar M, substantially as and for the uses and purposes set forth.

3. In an automatic car-coupling, frame A,

draw-bar B, draw-head D, movable lip E, lever F, cord or chain G, coupling-pin H, pivoted to an arm, I, bent lever J, having arm K, lever L, bearing pin l, and bar M, the whole combined and arranged to operate substantially as shown and described.

5 In testimony that I claim the foregoing I

have hereunto set my hand in the presence of two witnesses.

GEO. W. SMITH.

Witnesses:

EDWIN MOORE,
B. F. BEINE.
